(57) CLAIM

The ornamental design for a incubator for newborn infants, as shown and described.

DESCRIPTION

FIG. 1 is a first perspective representational view of the incubator for newborn infants with all doors closed;

FIG. 2 is a second perspective representational view of the incubator for newborn infants with all doors closed;

FIG. 3 is a first side view of the incubator for newborn infants with all doors closed;

FIG. 4 is a second side view of the incubator for newborn infants with all doors closed;

FIG. 5 is a first end view of the incubator for newborn infants with all doors closed;

FIG. 6 is a second end view of the incubator for newborn infants with all doors closed;

FIG. 7 is a top side view of the incubator for newborn infants with all doors closed;

FIG. 8 is a bottom side view of the incubator for newborn infants with all doors closed;

FIG. 9 is a first perspective view of the incubator for newborn infants showing the top doors partially opened and the end door opened;

FIG. 10 is a first perspective view of the incubator for newborn infants showing the top doors closed but rotated in a first direction so as to expose a pair of hand holes, with the end door open;

FIG. 11 is second perspective view of the incubator for newborn infants showing the top doors partially opened;

FIG. 12 is a second perspective view of the incubator for newborn infants showing the top doors closed but rotated in a second direction, with the end door open;

FIG. 13 is a side view of the incubator for newborn infants showing the top doors partially opened, with the end door open;

FIG. 14 is a first side view of the incubator for newborn infants showing the top doors closed but rotated in a first direction so as to expose a pair of hand holes, with the end door open;

FIG. 15 is a second side view of the incubator for newborn infants showing the top doors closed but rotated in a first direction, with the end door open;

FIG. 16 is a first end view of the incubator for newborn infants showing the top doors partially opened, with the end door open; and,

FIG. 17 is a top side view of the incubator for newborn infants showing the top doors partially opened, with the end door open.
